UNITED STATES PATENT OFFICE

2,449,827

RENEWABLE FUSE

Fred G. von Hoorn, Nichols, Conn., assignor to
General Electric Company, a corporation of
New York

Application August 27, 1947, Serial No. 770,823

1 Claim. (Cl. 200—131)

1

The present invention relates to electric fuses and more particularly to renewable enclosed cartridge fuses.

It is an object of the present invention to provide an improved renewable fuse having a minimum number of loose parts and in which the interior of the fuse cartridge is completely accessible for the ready removal of blown link sections. A still further object is to provide a conveniently renewable fuse which is inexpensive to manufacture.

Other objects of the invention as well as novel features of construction will be apparent from the following description taken in connection with the accompanying drawing in which Fig. 1 is an elevation of my fuse partly in longitudinal section; Fig. 2 is a section taken along the line 2—2 in Fig. 1; Fig. 3 is an elevation of one end of my fuse in a stage of manufacture; Fig. 4 is a section taken along the line 4—4 in Fig. 3; and Fig. 5 is an exploded perspective view of one end of my fuse cartridge.

My improved fuse comprises a fuse link containing cartridge having a tubular casing 1 of suitable insulating material. The ends of the casing 1 are reduced in diameter and exteriorly threaded as at 2 and 3. Engaging the threads 2 at the upper end of the fuse as viewed in Fig. 1 is a metal bushing 4 which is secured to the casing 1 in any suitable manner, as for example, by the pin 5. The bushing 4 is cup-shaped, thereby closing the end of the casing except for a slot 6 adapted to receive the end of a fuse link 7 in such a manner that the end of the link 8 may be bent over against the outside end of the cup-shaped bushing 4. The outside of the bushing 4 is threaded as indicated at 9 to receive a threaded cap 10. The inside end of the cap 10 is provided with a boss 11 adapted when the cap is screwed into place to press against and make firm electrical contact with the end 8 of the fuse link 7.

At the opposite end of the casing 1 the threads 3 are engaged by a metallic, interiorly threaded bushing 12, which is secured to the casing in any suitable manner, as by means of a pin 13. The bushing 12 is made from a simple cylinder preferably having an internal diameter greater than the internal diameter of the casing. This bushing is exteriorly threaded at 14 to receive an interiorly threaded end cap 15 which is in all respects similar to and interchangeable with the cap 10 at the other end of the fuse. Below the threads 14 the cylindrical bushing is made of reduced cross section as indicated at 16. Along the bottom edge of the bushing 12 there is hinged a fuse link sup-

2

porting member 17 over which the end 18 of the fuse link 7 can be bent. When a new link is installed in the fuse, the end 18 of fuse link 7 is held in place by the boss 19 of the cap 15.

An important feature of my invention resides in the manner of construction and attachment of the hinged member 17. As illustrated in Fig. 3, the initially cylindrical bushing 12 with its reduced diameter end portion 16 has cut into its edge a T-shaped slot 20. The opposed projections formed by the metal adjacent the slot, that is the projections 21 and 22, are then bent inward and flattened, thereby forming a hinge pin for the member 17, as shown in Figs. 4 and 5. The hinged member or door 17 is formed from sheet metal and is shaped substantially as shown in Figs. 2 and 5. It is large enough to cover somewhat more than one-half of the end of the bushing 12. One of its edges 23 is straight so that the end 18 of the fuse link can be bent over against it. The other edges of the member 17 are shaped to conform to the perimeter of the bushing end 16. The edge opposite the edge 23 is, however, formed with a tang 24, which is bent, initially as shown in Fig. 5 and finally substantially completely closed as shown in Fig. 1, to form the eye of the hinge and is adapted to engage the hinge pin formed by the bent projections 21 and 22 of the bushing.

The inner surface of the member 17 is provided with upwardly extending projections or bosses 25 and 26 which are located so as to fall just inside the end 16 of the bushing 12, thereby serving to locate the member 17 properly when the fuse is assembled and permitting a loose fit in the hinge.

In the assembly of my fuse the cup-shaped bushing 4 is first tightly screwed to the casing 1 and fixed to it as by the pin 5. The bushing 12 in its initial cylindrical form is then tightly screwed to the other end of the casing and fixed to it as by the pin 13. Thereafter, the slot 20 is pierced in the edge of bushing 12 and located so as to be on the same side of the casing as the slot 6 in the end of bushing 4. Subsequently, the projections 21 and 22 are bent inward and flattened, forming a hinge pin which is engaged by the hooked tang 24 of the member 17. Finally, the end of tang 24 is closed down, thereby forming a complete hinge and securely hinging the member 17 on the end 16 of the bushing 12. The fuse link 7 can then be inserted in the casing, its end 8 projecting through the slot 6 and being bent over the end of the bushing 4 as shown in Fig. 1. The other end 18 of the fuse link 7 is then bent over

the hinge member or door 17, and finally both end caps 10 and 15 are screwed into place.

In replacing a blown fuse link, the end caps 10 and 15 are removed, if necessary with the aid of the screw driver slots 27, and the hinged door member 17 opened, whereupon the blown fuse link sections will readily fall out of the casing. The door 17 is then closed and a new fuse link inserted, as described above.

It will be evident to those skilled in the art that my improved hinged closure plate construction may, if desired, be used at both ends of the fuse.

It will be observed that with my improved construction there are no loose parts in my fuse which may readily become lost, or which may inadvertently be omitted in reassembling the fuse. Moreover, full access to the interior of the fuse casing is provided by the door 17; the latter, because of the construction and positioning of its hinge outside of the internal boundary (prolonged) of the casing, does not in any way provide any obstruction in the interior of the fuse on which blown fuse link portions may catch. Moreover, the hinge, being positioned on the perimeter of the bushing, will not be subjected to the full force of a blowing fuse link, and thereby will not be likely to become badly fouled. This location of the hinge also permits the hinged member to swing open nearly a full 180 degrees. It will further be noted that my fuse construction is substantially completely gas tight and will pass the severe requirements of the underwriters. Finally, it will also be evident that my fuse parts can be made with simple tools and can, therefore, be produced at a low cost.

What I claim as new and desire to secure by Letters Patent in the United States is:

5 In a refillable fuse member having an insulating casing, a metallic open ended bushing at one end of the casing, a cover plate partly closing the open end of the bushing and adapted to have one end of a fuse link bent to lie along the outer surface of said plate and an end cap detachably secured to said bushing and adapted when tight to 10 clamp the fuse link against said plate; the combination therewith of a hinge for said cover plate comprising a tang extending from one edge of said plate, said tang being bent toward the inner surface of the plate into an eye adapted to engage a hinge pin, the end of said bushing having a T-slot in its periphery with the stem of the T extending to the end of the bushing forming opposed tongues, said tongues being bent inwards and flattened and being thereby adapted together to form 15 a hinge pin at the end of the bushing for receiving said eye.

20 FRED G. VON HOORN.
